ard Sanitary Corporation, Pittsburgh, Pa., a corporation of Delaware

Application January 2, 1953, Serial No. 22,967

Term of patent 14 years

(Cl. D33—19)

To all whom it may concern:

Be it known that we, Harry R. Trout and Frederick M. Hill, citizens of the United States, residing at Pittsburgh, State of Pennsylvania, have invented a new, original, and ornamental design for a Kitchen Base Cabinet, of which the following is a specification, reference being had to the accompanying drawing, forming a part hereof.

The figure is a perspective view showing one side and the front of the kitchen base cabinet, embodying our new design.

We claim:

The ornamental design for a kitchen base cabinet, substantially as shown.
